(57) **CLAIM**

The ornamental design for a surface configuration of a front end of a vehicle, as shown and described.

DESCRIPTION

This application is related to the following co-pending applications, of the inventor, filed on even date herewith: U.S. patent application Ser. No. 29/151,801, entitled "Surface Configuration of a Vehicle and Toy"; U.S. patent application Ser. No. 29/151,819, entitled "Surface Configuration of a Front Bumper For a Vehicle"; U.S. patent application Ser. No. 29/151,807, entitled "Surface Configuration of a Front Bumper For a Vehicle"; and U.S. patent application Ser. No. 29/151,815, entitled "Surface Configuration of a Front End of a Vehicle".

FIG. 1 is a front view of a surface configuration of a front end of a vehicle according to my novel design; and,

FIG. 2 is a perspective view of the surface configuration of a front end of a vehicle according to my novel design.

The broken lines included in the drawings depict environment and are not part of the claimed design.
